UNITED STATES PATENT OFFICE.

ADAM P. THOMASSON, OF CHICAGO, ILLINOIS.

HEATING STOVE.

1,416,140.

Specification of Letters Patent. Patented May 16, 1922.

Application filed October 31, 1921. Serial No. 511,557.

To all whom it may concern:

Be it known that I, ADAM P. THOMASSON, a citizen of the United States, and a resident of the city of Chicago, county of Cook and State of Illinois, have invented certain new and useful Improvements in Heating Stoves, of which the following is a specification.

My invention relates to new and useful improvements in heating stoves, and has for its principal object the provision of an improved construction of this character which will be highly efficient in use.

A further object of my invention is the provision of a heating stove, whereby the fresh fuel can be fed under the bed of burning fuel. In this respect I have found that in burning soft coal, such as is commonly called Pocahontas or mine run coal, in a heating stove, that the small lumps of coal, during combustion, unite into one large lump of partially burned fuel which cling to the sides of the stove and usually constitute the crust of the top layer of the fire bed. It has been my experience that as long as there is a combustion of fuel under the top layer or crust thus formed, the partially burned fuel, or cinders, as they are commonly called, will radiate heat but as soon as the combustion of the fuel dies out, the partially burned fuel will cease to radiate heat. It is, therefore, my object to provide a means whereby fresh fuel can be conveniently fed under the lump or lumps of partially burned fuel, which will keep the partially burned fuel in a state of combustion.

Other objects will appear hereinafter.

The invention consists in the combinations and arrangements of parts hereinafter described and claimed. The invention will be best understood by reference to the accompanying drawing forming a part of this application, and in which,

Fig. 1 is a side elevational view of my improved heating stove, partly broken away to more fully illustrate the broad construction embodied in the invention.

Fig. 2 is a sectional detail view of the same taken substantially on line 2-2 of Fig. 1, and

Fig. 3 is a sectional detail view of the same, taken substantially on line 3-3 of Fig. 1.

The preferred form of construction, as illustrated in the drawing, comprises a heat-

ing stove 5 of any approved type having a grate 6, and an ash pit or box 7, mounted on supporting legs 8. Mounted on the heating stove 5, as shown, is a fuel feeding hopper 9 which receives the fresh fuel 10 which is discharged through an opening 11, formed in the wall of the fire pot of the heating stove 5, under the layer of lumps 11' containing cinders and other unburned particles of combustion. The hopper 9 is preferably a casting provided with flanges 12 affording means for securing the hopper in position, as shown in Fig. 1 of the drawing.

The hopper, however, may be formed of sheet metal or any other suitable material which will serve the purpose. The top wall 13 of the hopper 9 is provided with an opening 14, through which the fuel is discharged into the hopper, and is provided with the usual closure or lid member 15, such as is employed in connection with most every approved heating stove.

In most coal stoves it has been found that at times the gases from the fire pot escape through the small crevices between the edge of the opening 14 and the lid 15. To prevent the escape of such gases I provide an outer closure member 16, of any approved type, and which is hingedly mounted on the side wall of the heating stove, by any suitable means. The outer closure member 16 is provided with a semi-annular depending flange 17 having a semi-annular flange 18, integrally formed therewith, and which rests upon the top wall 13 of the hopper, supporting the top of the closure member in spaced relation with respect to the lid or top wall of the hopper.

The gases escaping from the hopper into the space between the top of the hopper and closure member is drawn, by the force of the draft of the heating stove, back into the upper portion of the combustion chamber through a plurality of aligned ports 19. By this arrangement it is obvious that the gases from the fire pot are not permitted to escape into the room where the stove is located, but will be drawn back into the combustion chamber through the ports 19, as will be readily understood.

As is clearly shown in Fig. 1 of the drawing, a portion of the side wall, above the opening 11, is flexed inwardly, as at 12'. This arrangement is such that when feeding the fresh fuel into the fire pot under the top

layer of united cinders, the fresh fuel is prevented from being thrown or poked on top of the united cinders 11'.

In use, a fire is built in the fire pot, in the usual manner, the fresh fuel 10 being fed into the fire pot through the hopper 9. After the fuel has practically been consumed, the ashes, through the medium of a shaker grate, (not shown), are discharged into the ash pit or box 7. It has been found that after the ashes have been discharged from the fire pot into the ash pit, there remains a crust of the fire bed which is formed by the melting together of the partially burned fuel, and which clings to the walls of the heating stove forming a space or recess between the crust thus formed and the fire grate. It is my object to utilize this crust or top layer by radiating heat therefrom. In order to radiate heat from the crust, or top layer of the fire bed, it is necessary to constantly feed fresh fuel into the space between the remaining crust and the fire grate. This is done through the medium of the hopper 9 and the fuel thus fed into the space serves to support this crust and consume the unburned fuel remaining in the crust formed on the top of the fire bed. Thus, by the construction of a heating stove, as herein set forth, the cinders clinging to the side walls of the heating stove, which are often discharged into the ash pit, are all consumed into ashes and then discharged into the ash pit.

While my improved heating stove is especially designed for burning soft coal, in the manner hereinbefore stated, hard coal as well as moist ashes containing unburned fuel may be burned in the stove as well. In burning moist ashes containing unburned fuel, the ashes are discharged on top of the upper layer or crust 11' of the fuel bed through the opening 20 provided on the top wall of the heating stove 5. The flexed portion 12' prevents the ashes from being discharged into the hopper 9 and mixing with the fresh fuel 10.

By my improved means for feeding fuel to the lower portion of the fire bed, as herein stated, when burning moist ashes containing unburned fuel, the ashes are separated from the fresh fuel, that is, the lower portion of the fire bed, by the upper portion of the fire bed which constitutes the united lumps of partially burned fuel, or the crust 11', clinging to the side walls of the heating stove. Thus, the moist ashes, are separated from the fresh fuel of the fire bed and prevented from quenching the burning fuel under the crust or upper layer of the fire bed, and the moist ashes, containing unburned fuel, is melted into a melting, doughy form, generating an inflammable gas, which greatly adds to the combustion of the ashes and the fresh fuel.

By a heating stove, as herein disclosed, it is obvious that the stove will be a great fuel saver, inasmuch as very little, if any at all, of the fuel is discharged into the ash pit, for the arrangement is such that the fuel is consumed until nothing is discharged in the ash pit but pure ashes.

While I have illustrated and described the preferred form of construction for carrying my invention into effect, this is capable of variation and modification without departing from the spirit of the invention. I, therefore, do not wish to be limited to the precise details of the construction set forth, but desire to avail myself of such variations and modifications as come within the scope of the appended claims.

Having described my invention, what I claim as new and desire to secure by Letters Patent, is:

1. In a heating stove, the combination with the combustion chamber and fire pot thereof, of an opening in said fire pot; means for feeding moist ashes containing unburnt particles of combustion to said fire pot, a hopper fixedly secured to said stove and surrounding said opening; an inner closure member for the opening of said hopper; an outer closure member hingedly mounted on said apparatus and supported in spaced relation with said first mentioned closure member; and means for permitting the passage of gas into said combustion chamber from the space between said outer and inner closure members, substantially as described.

2. In a heating stove, the combination with the combustion chamber and fire pot thereof, of means for feeding moist ashes containing unburned fuel to said fire pot; a hopper for feeding fresh fuel into said fire pot; an inner closure member for the opening of said hopper; an outer closure member for said hopper and supported in spaced relation with respect to said first mentioned closure member; and a plurality of ports formed in the side wall adjacent to said closure members for permitting the passage of gases into said combustion chamber from the space between said outer and inner closure members, substantially as described.

3. The combination with a heating stove having a combustion chamber and a fire pot, of an opening in said fire pot; a hopper surrounding said opening and fixedly secured to said heating stove for feeding fuel to the lower portion of the fire bed in said fire pot, the side wall portion of said heating stove above said opening being flexed inwardly to prevent the particles of combustion of the upper portion of said fire bed from being discharged into said hopper; an opening in the top wall of said hopper; a closure member for said opening; an outer closure member hingedly mounted on said

heating stove and supported in spaced relation with respect to said first mentioned closure member; and a plurality of aligned ports formed in side wall of said heating stove for permitting the escape of gases into said combustion chamber from said space between said closure members, substantially as described.

In testimony whereof, I have signed my name to this specification in the presence of 10 two subscribing witnesses.

ADAM P. THOMASSON.
